UNITED STATES PATENT OFFICE.

McCLELLAN RUSAN, OF MANITOU SPRINGS, COLORADO.

AIR-SCREEN FOR WINDOWS AND DOORS.

1,094,680.

Specification of Letters Patent. Patented Apr. 28, 1914.

Application filed September 15, 1911. Serial No. 649,412.

To all whom it may concern:

Be it known that I, McCLELLAN RUSAN, a citizen of the United States, residing at Manitou Springs, in the county of El Paso 5 and State of Colorado, have invented a new and useful Air-Screen for Windows and Doors, of which the following is a specification.

This invention has for its object to provide novel means for preventing the ingress of insects and other foreign objects through windows and doors, and is embodied in certain novel arrangement and construction of parts as hereinafter described and as 15 pointed out in the claims.

The invention is illustrated in the accompanying drawings, wherein similar reference characters indicate similar parts, and wherein:

20 Figure 1 is an elevation of an embodiment of the present invention. Fig. 2 is a section on the line 2—2 of Fig. 1. Fig. 3 is a section on the line 3—3 of Fig. 1.

In carrying out the present invention 25 there is employed a wooden frame F which comprises a pair of stiles and a rail connecting their upper ends, the frame being a three sided structure, in order that it may be applied over a door, although it is to be 30 understood that a four sided structure may be employed in connection with windows, as will be apparent. The stiles and rails each embody a wooden or similar bar 5, which is designed for attachment to a window or door frame, and a cleat 6, of wood 35 or similar material secured to the inner edge of and arranged at right angles to the bar 5. The free portion of the cleat 6 is beveled away from the bar 5, as clearly seen 40 in Figs. 2 and 3.

Attached to the frame F, is an air chamber or tube C, which comprises a number of sections secured to the respective sections or parts of the frame. Each section of the 45 air chamber or tube C is formed of a plate or strip of sheet metal, which is doubled and bent longitudinally to provide a flat back 12 resting against the respective bar 5, and having an angular portion 13 at one 50 side resting against the bevel of the corresponding cleat 6, and a front 10 extending from the other side of the back to or toward the said angular portion 13, the front having an angular lip 14' coöperating 55 with the free portion 14 of the angular portion 13 to form a discharge nozzle.

zle. The coöperating portions 14 and 14' are doubled as at 15 and 15', the edges of the blank being bent back, and being secured together by means of rivets or 60 other securing members 18. The blank is doubled between the back 12 and the front 10 to form a flange 11, which engages a grooved shoulder 8 formed on the bar 5. The front 10 is curved in order that the lip 65 14' thereof may coöperate with the lip 14 of the angular portion 13.

Angular ears 16 are secured to the back of each section of the air chamber or tube, and project away from the elbow between 70 the back and the angular portion 13, the ears 16 of each section of the chamber projecting between the bar and the cleat, and being secured to the edge of the bar, whereby each section of the chamber will be locked 75 to the respective section of the frame, with the angular portion 13 and lips forming the nozzle, locked against the bevel of the cleat 6. The ears 16 are preferably secured to the bars 5 by means of nails or other securing 80 members 9. The adjoining ends of the chamber sections are mitered together, as well as the sections of the frame, whereby a continuous nozzle N will be provided around the corners of the frame, the nozzle being 85 coextensive with the frame.

One section of the air chamber is provided with a nipple 17, to which is connected a suitable air supply pipe 30, when the device is applied over a door or window, in order 90 that air or other fluid may be supplied to the air chamber so as to be discharged from the nozzle N over the door or window opening. It is evident that when the air is admitted into the chamber, the same will be 95 discharged in a thin film or sheet from the nozzle N, the streams or films of air converging, so as to preclude the ingress of insects or other foreign objects through the window or door opening. A rod 20 is preferably secured to the nozzle portion of the upper section of the air chamber, and has a fly scare 21 of thin gauze hung therefrom, so that the air will raise and flap the fly scare to assist in scaring flies and other 100 insects away from the door or window opening.

The present device is readily applied to a window or door frame, by attaching the bars 5 of the frame to the window or door 110 frame, as will be apparent.

The present device permits an unobstruct-

ed opening, through which large objects may be conveniently passed, it being noted that when the device is applied to a door frame, there will be no obstruction to the passage of persons through the door.

The advantages of the present device over the ordinary meshed wire screen, as ordinarily employed, will be apparent without lengthy description.

What is claimed as new is:

1. In a device of the character described, a frame embodying a bar, and a cleat secured to one edge of and arranged at right angles to the bar, the cleat being beveled away from the bar; and an air tube embodying a back resting against the said bar and having an angular portion at one side resting against the said bevel of the cleat, and a front extending from the other side of the back to the said angular portion and having an angular lip coöperating with said angular portion to form a discharge nozzle, the back of the tube having means engaging between the bar and cleat.
2. In a device of the character described, a frame embodying a bar, and a cleat se-

cured to one edge of and arranged at right angles to the bar, the cleat being beveled away from the bar; and an air tube formed of a sheet metal blank doubled and bent longitudinally to form a flat back resting against the said bar and having an angular portion at one side resting against the said bevel of the cleat, and a curved front extending from the other side of the back toward the said angular portion, and having an angular lip coöperating with the said angular portion to form a discharge nozzle, the blank being formed with a flange at the last mentioned side of the back, the said flange engaging the aforesaid bar, and the back of the tube having means at the elbow between the back and the said angular portion engaging between the said bar and cleat.

In testimony that I claim the foregoing as my own, I have hereto affixed my signature in the presence of two witnesses.

McCLELLAN RUSAN.
